BLINKER SIGNAL LIGHT

Carl Rosen, 8221 E. 3rd St., Downey, Calif. 90241

Filed Jan. 9, 1967, Ser. No. 5,355

Term of patent 14 years

(Cl. D48—24)

FIG.1

FIG.2

FIG.3

FIG.4

FIG.5

FIGURE 1 is a front perspective view of a blinker signal light showing my new design;

FIGURE 2 is a front elevational view thereof;

FIGURE 3 is an elevational view taken from one side thereof, the opposite side being the same as the side shown;

FIGURE 4 is a top plan view thereof; and

FIGURE 5 is a bottom plan view thereof.

I claim:

The ornamental design for a blinker signal light, substantially as shown and described.
